WIRE STRAIGHTENING APPARATUS

August Wennerberg, Chicago, Ill., assignor to
 Western Electric Company, Incorporated, New
 York, N. Y., a corporation of New York

Application October 12, 1943, Serial No. 505,906

4 Claims. (Cl. 140—147)

This invention relates to wire straightening apparatus and more particularly to a rotary type wire straightening apparatus.

An object of the invention is to provide a simple and practicable apparatus for straightening advancing wire in an efficient and rapid manner.

In attaining this object, there is provided, in one embodiment of the invention, an apparatus comprising a pair of spaced coaxially arranged rotary tubular elements interconnected by a tubular member, in which is carried a circular bar having a radial slot terminating at its inner end in alignment with the apertures in the elements. Extending through the aligned apertures in the elements and the bar slot and fixed at opposite ends to the elements is a flexible tube, which is curved to sinusoidal-like shape into the bar slot by an adjustable screw engaging it laterally intermediate the elements and a pair of spaced shoes engaging the opposite side thereof at each side of the screw, one of the shoes being adjustable longitudinally of the tube whereby, upon releasing the adjacent end of the tube from the associated element and adjusting the screw, the amplitude of the curve in the flexible tube may be varied to suit the particular wire to be straightened. A pulley connected to one of the elements and driven by a belt serves to rotate the entire unit as the wire is advanced therethrough, thereby subjecting it to a universal bending action which is effective to remove all bends which were in the wire when it entered the apparatus.

Other objects and advantages of this invention will more clearly appear from the following detailed description, taken in conjunction with the accompanying drawing, in which

Fig. 1 is a plan view, partly in section, of a wire-straightening apparatus embodying the features of this invention;

Fig. 2 is a longitudinal central vertical section, partly in elevation, of the apparatus shown in Fig. 1; and

Figs. 3 and 4 are vertical sections taken on the lines 3—3 and 4—4, respectively, of Fig. 2.

Referring to the drawing and more particularly to Fig. 2, a base is indicated at 10, to opposite ends of which are attached vertical standards 11 and 12 provided at their upper ends with aligned openings 13. Secured to the standards 11 and 12 by screws 14 and having reduced portions thereof entered in the openings 13 are externally shouldered bearing members 15 supporting radial ball bearing assemblies 17, which ro-

tatably support surrounding internally and outwardly shouldered tubular heads 18 and 19 having aligned openings 20 and 21, respectively. The inner and outer ball races are press fitted into the member 15 and the heads 18 and 19, respectively. The heads 18 and 19 are interconnected by a tubular member 24, which is fixed to rotate therewith by radially directed pins 25. Enclosed in the tubular member 24 is a circular bar 26, which is secured for rotation with the members 15 by radially directed pins 27. Press fitted into the aligned openings 13 of the members 15 and the openings 20 and 21 of the heads 18 and 19 and rotatable therewith are externally shouldered sleeves 28 and 29.

Formed in the bar 26 throughout its length is a radially directed slot 32 having its inner end wall 33 in alignment with openings 34 in the sleeves 28 and 29. Entered in the aligned sleeve 20 openings 34 and the bar slot 32 is a flexible tube 35 of a well-known construction comprising inner and outer interlocked spiral layers of material, preferably metal. Entered in the slot 32 are spaced abutments or shoes 36 and 37, the shoe 36 being pinned, as indicated at 40, to the left end of the bar 26 (Fig. 2), and the shoe 37 being mounted for longitudinal adjustment along the slot at the right end thereof. For the purpose of accurately guiding the shoe 37 along a fixed path, it is formed with opposite key formations 41, which ride in keyways 42 provided in opposite walls of the slot. The bottom faces of the shoes 36 and 37 at their inner opposed ends are suitably curved, as indicated at 43 and 44, respectively, for engagement with the tube 35 for a purpose which will be presently described. At its upper end, the shoe 37 is provided with a pair of spaced ears 47, which project through a longitudinally extending slot 48 formed in the tubular member 24. The right end of the member 24 is provided with a peripheral screw thread 49 and threaded thereonto is an adjustable collar 50 having a plurality of laterally extending apertures 51, in the present embodiment spaced 45 90° apart, the collar being entered between the shoe ears 47. A cotter pin 54 entered in aligned apertures in the ears 47 and one of the apertures 51 of the collar 50 serves to retain the shoe 37 and collar in their adjusted position longitudinally of the flexible tube 34.

To adjust the shoe 37 to another position, the cotter pin 54 is removed and the collar 50 rotated one way or the other, which will cause the shoe to move longitudinally of the tube 35. When 55 the adjustment is completed, the cotter pin 54

is replaced in the aligned apertures in the ears and the collar. Threaded into the bar 26 opposite the slot 32 and intermediate the shoes 36 and 37 is an adjustable screw 55, which, at its inner end, extends into the slot and engages the flexible tube 35 to bend it laterally into the slot out of alignment with and eccentric to its opposite aligned ends. Portions of the tube 35 at each side of the screw 55 and opposite thereto are then pressed into engagement with the curved bottom faces 43 and 44 and the shoes 36 and 37, respectively, the tube being bent or curved to a sinusoidal-like shape between the shoes. After the flexible tube 35 has been bent out of alignment with its opposite ends carried in the sleeves 28 and 29 to provide the desired shape thereto to suit the particular wire to be straightened, which it will be obvious can be readily effected by adjusting the shoe 37 longitudinally of the tube and the screw laterally thereof in the manner previously described, the ends of the tube are fixed to the sleeves by clamping split heads 56 of the sleeve to the tube ends by means of screws 57. The length of the tube 35 is such that in all possible shapes it may be adjusted to, it extends outwardly slightly from the split clamping heads 56. Thus, an advancing wire to be straightened, indicated at 58, bears solely on the wall of the tube, which can be readily replaced due to wear thereon. Fixed to the head 18 by a set screw 59 is a pulley 60, which is driven by a belt 61 receiving motion from a suitable source (not shown).

In the use of the apparatus, the wire 58, which is to be straightened, is led from its supply and threaded through the flexible tube 35 and connected to a take-up device. With the wire 58 advancing through the apparatus at a suitable speed and the rotatable unit of the apparatus, including the flexible tube 35, rotating at a suitable speed, the wire is subjected to a universal bending action, which is effective to remove all bends or irregularities therein from straightness which were in the wire when it entered the apparatus.

From the foregoing description, it will be apparent that a simple and practicable wire-straightening apparatus is provided employing a flexible rotating straightening tube in which the amplitude of the eccentric bent portion intermediate its ends may be readily varied to suit the particular wire being straightened.

It will be readily understood that the embodiment herein described is merely illustrative of the invention and that modifications can be made.

What is claimed is:

1. An apparatus for straightening advancing wire comprising spaced axially aligned rotary sleeves, connecting means between said sleeves whereby they rotate in unison, said connecting means having a laterally extending longitudinal slot, a flexible tube having its opposite ends communicating with and axially connected to said sleeves for rotation therewith, said tube between said sleeves being entered in said slot and bodily curved laterally to a sinusoidal-like shape out of alignment with said sleeves, the wire being

advanced through said tube, spaced abutments in said slot engaging portions of the tube, means adjustable on said connecting means and operatively engaging one of said abutments for moving the same longitudinally of said slot, and means arranged between said abutments and cooperating with said connecting means for maintaining the tube curved.

2. An apparatus for straightening wire comprising a cylindrical element having a radial slot, a flexible tube in said slot, means for rotating said element with the ends of the tube coincident with the axis of rotation, an intermediate portion of the tube being in curved form, abutments in opposite ends of said slot having curved faces engaging spaced portions of the tube, a rotatably mounted member bodily movable longitudinally of and surrounding said element and operatively engaging one of said abutments for moving the same longitudinally of said slot, and means carried by said element intermediate the abutments and engaging the opposite side of the tube for maintaining the tube in engagement with said abutments in curved form in the slot.

3. An apparatus for straightening wire comprising a cylindrical element having a radial slot, a flexible tube in said slot, means for rotating said element with the ends of the tube coincident with the axis of rotation, an intermediate portion of the tube being in curved form, an abutment fixed in one end of said slot, a second abutment in the opposite end of and movable along a fixed path longitudinally of said slot, said abutments having curved faces engaging spaced portions of the tube, means for adjusting said second abutment, and means intermediate the abutments and engaging the opposite side of the tube cooperating with said abutments for maintaining the tube in engagement with said abutments in predetermined curved form in the slot.

4. An apparatus for straightening wire comprising a cylindrical element having a radial slot, a sleeve fixed to and surrounding said element, a flexible tube in said slot, means for rotating said element and sleeve with the ends of the tube coincident with the axis of rotation, an intermediate portion of the tube being in curved form, an abutment fixed in one end of said slot, a second abutment in the opposite end of and movable along a fixed path longitudinally of said slot, said abutments having curved faces engaging spaced portions of the tube, a collar screw threaded onto and adjustable along said sleeve, said second abutment having portions extending through a slot in said sleeve and operatively connected to said collar effective for adjusting said second abutment upon rotation of said collar, means for retaining said collar and abutment in their adjusted positions, and means extending through an opening in said sleeve and carried by said element intermediate the abutments and engaging the opposite side of the tube cooperating with said abutments for maintaining the tube in engagement with said abutments in predetermined curved form in the slot.

AUGUST WENNERBERG.
